DESIGN FOR A LITURGICAL FABRIC OR SIMILAR ARTICLE

William T. Mulloy, Covington, Ky.

Application March 22, 1949, Serial No. 1,553

Term of patent 7 years

(Cl. D92—1)

To all whom it may concern:

Be it known that I, William T. Mulloy, a citizen of the United States of America, residing in Covington, county of Kenton, and State of Kentucky, have invented a new, original, and ornamental Design for a Liturgical Fabric or Similar Article, of which the following is a specification, reference being had to the accompanying drawing, forming part thereof.

In the drawing the figure is a plan view of the liturgical fabric, embodying my design.

I claim:

The ornamental design for a liturgical fabric or similar article, substantially as shown.

WILLIAM T. MULLOY.
